UNITED STATES PATENT OFFICE.

ARTHUR P. CROSBY, OF MINNEAPOLIS, MINNESOTA, ASSIGNOR OF ONE-HALF TO
WILLIAM T. PRICE, OF MINNEAPOLIS, MINNESOTA.

AIR EXHAUST FOR VAPOR-HEATING SYSTEMS.

1,425,370.

Specification of Letters Patent.

Patented Aug. 8, 1922.

Application filed January 24, 1921. Serial No. 439,420.

To all whom it may concern:

Be it known that I, ARTHUR P. CROSBY, a citizen of the United States, residing in Minneapolis, in the county of Hennepin and 5 State of Minnesota, have invented a new and useful Air Exhaust for Vapor-Heating Systems, of which the following is a specification.

The object of this invention is to provide 10 efficient, simple, inexpensive and easily accessible means for sucking or exhausting air out of radiators as it tends to accumulate therein, to prevent any water or vapor forcing back into any of the radiators and 15 to prevent the water seal or siphon breaking and allowing vapor or steam to short circuit or rush back to the boiler through any radiator in a heating system, thereby causing a vapor heating system to operate more 20 effectively and the radiators thereof to maintain a constant and even temperature.

In the drawing, Fig. 1 is a vertical central section through my improved return seal and Fig. 2 is a side elevation of a radiator and one of my improved return seals attached thereto.

My return seal A is adapted to automatically suck or draw air from a radiator and comprises a receptacle having a casing 5, in 30 its upper portion of which is threaded a removable cover 6 and at the lower portion of which is an internally threaded nipple 7, said nipple being connected with the return pipe 3. The upper end of the casing 35 has an externally threaded nipple 8, which is connected by the coupling 9 with the lower outlet end of the radiator, such as B. Entering the nipple 7 is a small vertical passage 10, which extends upwardly through 40 an inverted U shaped duct, seal or siphon D, the short leg 12 of which is reversed upwardly at its lower end 13 and terminates in a valve seat 14 a short distance above the bottom of the receptacle. A partition 15 is 45 thus established between the long and short legs of what might be termed a siphonic discharge. In the arch of the duct, above the partition 15, is a small vent 16 communicating with the passage leading into the 50 radiator, said vent lying normally above the level of the liquid in the duct or seal. The valve seat 14 is adapted to be closed by a small ball float valve 17 which plays freely in the space between the sides of the casing

5 below a stop 18, which is formed on the 55 side of the siphon tube.

When vapor or steam is first admitted to a cold radiator, there will be a much greater accumulation of water of condensation and also a larger volume of air to dispose of 60 than when the radiator becomes heated. This water of condensation is in sufficient volume to fill the trap or receptacle, lift the valve 17 into open position, overflow the 65 wall or dam 15 and fill the arch above said wall sufficiently to start siphonic action. As soon as this action is established, the air will be drawn out of the radiator and the vapor be allowed to fill all of its sections. Should the out-rush of water of condensation 70 nearly exhaust or break the siphon column of water, the ball valve will lower with the water in the casing and close over the valve seat 14, thus checking this tendency and maintaining the water seal produced by 75 the siphon. The siphonic discharge is maintained so long as condensation continues and until substantially all of the air is withdrawn and the walls of the radiator thoroughly heated. After the radiator becomes 80

heated, the volumes of water of condensation will be automatically reduced and thereupon the liquid in the trap will form a seal and prevent the passage of the vapor through the radiator. The slight accumulation of water of condensation after the radiator is once thoroughly heated is disposed of by the overflow over the upper edge of the dam 15, but the seal is never completely 85 broken, due to the ball valve checking the 90 egress of liquid from the siphon. This action is repeated automatically whenever the walls of the radiator become reduced in temperature. The port 16, in connection with the siphonic action, has a pumping effect on 95 the radiator and automatically prevents the accumulation of air therein and the non-heating of the radiator sections. The vapor and air, it will be noted, are separated through the accumulation of water of condensation and the air removing means becomes effective only when the water is in sufficient quantity to prevent or retard the heating of the sections and at this time condensation will be sufficiently rapid to set up 100 siphonic action and remove the air accumulation. During this operation a flapper check valve E prevents the return flow of 105

any water or vapor into and the flooding of the radiator, due to any cause such as the uneven distribution of water and vapor throughout the entire heating system and 5 the shutting or turning on of any radiators by the usual valves, such as 19 in the feed pipe 20. This check valve E is very sensitive and is hingedly hung by the pintle 21 in a bushing 22, which is fitted closely in 10 the ingress duct 20 in nipple 8.

In case the radiator is shut off by the valve 19, the water in the seal is prevented from freezing by the second vent passage 24 in the lower end of the long leg of the 15 siphon or seal, said vent allowing nearly all of the water in the receptacle to flow back to the vapor generator through the return pipe 3.

Having described my invention, what I 20 claim as new and desire to secure by Letters Patent is:

1. A return seal for a vapor system, comprising, a casing having ports in communication with a radiator and with a return 25 pipe, a siphon mounted in said casing and communicating with said return pipe and having a restricted passage in the upper wall of the arch of the siphon above the level of the liquid when siphonic action begins and 30 through which passage air is sucked from the radiator intermittently to break the siphon, a check valve in the radiator port adapted to automatically check flow into the radiator and a check valve in the lower end 35 of the short leg of the siphon adapted to prevent the liquid in the siphon from entirely exhausting.

2. A return seal for a vapor system, comprising a casing having ports in communication with a radiator and with a return 40 pipe, a siphon mounted in said casing and

communicating with said return pipe and having a restricted passage above the normal level of the water when siphonic action begins and communicating with said return 45 pipe, said siphon having a second restricted passage communicating with said return pipe and located near the bottom of said casing, a check valve in the radiator port adapted to automatically check return flow 50 into the radiator and a check valve in the lower end of the short leg of the siphon adapted to prevent the liquid in the siphon from entirely exhausting.

3. An air exhaust for vapor or steam heating systems, comprising a trap having a siphonic discharge and a port for communication with a heat radiating means and a restricted passage in communication with the arch of the siphon and above the normal 55 level of the liquid when siphonic action begins, the water of condensation in said trap normally forming a seal for said heat radiating means and the accumulation of an abnormal volume of condensation in said 60 trap, as when said means is cold, setting up siphonic action intermittently to suck the air from said radiating means through said passage, the excess water in said trap co-operating with said passage to alternately 65 make and break the siphon until the air is removed from said head radiating means, a check valve in the port immediately above the siphon adapted to automatically check return flow into the radiator, and a float 70 valve in the trap adapted to automatically close the lower end of the short leg of the siphon and maintain the seal when the liquid in the trap lowers.

In testimony whereof, I have signed my 80 name to this specification.

ARTHUR P. CROSBY.
